UNITED STATES PATENT OFFICE.

ORVILLE L. PARMENTER, OF RACINE, WISCONSIN.

DESIGN FOR A CIGAR-WRAPPER.

SPECIFICATION forming part of Design No. 29,592, dated November 1, 1898.

Application filed September 24, 1898. Serial No. 691,825. Term of patent 7 years.

To all whom it may concern:

Be it known that I, ORVILLE L. PARMENTER, a citizen of the United States, residing at Racine, in the county of Racine and State 5 of Wisconsin, have invented and produced a new and useful Design for Cigar-Wrappers; and I do hereby declare the following to be a full, clear, and exact description of the invention, such as will enable others skilled in the 10 art to which it appertains to make and use the same.

This invention relates to a new and useful design for cigar-wrappers.

Referring to the accompanying drawings, 15 Figure 1 is a perspective view of the cigar-wrapper. Figs. 2 and 3 are edge views of opposite sides thereof.

The wrapper consists of a long narrow cell tapering to closed end *a* and also having a 20 general taper to the opposite end *b*, which is closed by a strip or piece *c*.

The wrapper has the generally flat faces *d* and sides *e*, which are formed with a multiplicity of perforations extending through the

material of the wrapper, so that each perforation will appear as a dark spot, whereby the perforated part of the wrapper is given a speckled appearance, as though covered with dark small spots or specks. A peculiar artistic effect is thus produced, rendering the 25 wrapper exceedingly striking in appearance by reason of the long narrow tapered wrapper having the perforations, whereby the essential feature of the design is the general shape of the cigar-wrapper with the plurality 30 of spots or specks scattered over the same.

Having thus fully described my invention, what I claim as new, and desire to secure by Letters Patent of the United States, is—

The design for a cigar-wrapper, substantially as shown and described.

In testimony whereof I affix my signature in presence of two witnesses.

ORVILLE L. PARMENTER.
